(57) **CLAIM**

The ornamental design for a quick release, as shown and described.

DESCRIPTION

FIG. 1 is an isometric view of a quick release.

FIG. 2 is a rear and front view of the quick release of FIG. 1.

FIG. 3 is a left and right view of the quick release of FIG. 1.

FIG. 4 is a plan view of the quick release of FIG. 1; and, FIG. 5 is a bottom view of the quick release of FIG. 1.

The rear and front views are identical due to symmetry. The left and right side views are identical due to symmetry. Broken lines in FIG. 5 form no part of the claimed design.

1 Claim, 2 Drawing Sheets
